UNITED STATES PATENT OFFICE.

ANTOINETTE VOSS, OF CHICAGO, ILLINOIS, ASSIGNOR TO HUGO DU BROCK, OF CHICAGO, ILLINOIS.

SANITARY GARMENT-SHIELD.

1,076,252.

Specification of Letters Patent.

Patented Oct. 21, 1913.

Application filed September 19, 1912. Serial No. 721,248.

To all whom it may concern:

Be it known that I, ANTOINETTE Voss, a citizen of the United States, residing at Chicago, in the county of Cook and State of Illinois, have invented certain new and useful Improvements in Sanitary Garment-Shields, of which the following is a specification.

The garment-shield which is the subject of the present invention is designed to be worn in connection with a catamenial bandage to prevent soiling of the outer garments, and it is the object of the invention to provide in a shield of this kind an improved means for attaching the bandage.

The invention also has for its object to provide a structure in which the parts are separable, thereby making them easier to be washed and kept in a sanitary condition.

In the accompanying drawing forming a part of this specification, a perspective view of the invention is shown.

Referring specifically to the drawing, the article comprises a shield or apron which is composed of a lower portion 5 and an upper portion 6, for which latter any suitable fabric may be employed. The lower portion of the shield may be of some water-proof, rubberized or similar fabric, and is sewed or otherwise connected to the upper portion. The top edge of the upper portion is capped with a ribbon or tape 7 to which is removably connected, by ordinary glove-snaps 8, the rear portion of a waist-band 9. Integral with the waist-band, at the rear portion thereof, is a depending flap 10. The waist-band is divided at the front and the two

ends thereof are detachably fastened to a small substantially trifoliate sheet 11 by safety pins or other suitable fasteners 12. 40 The lower end of the flap 10 is also fastened to the upper portion of the part 5 by glove-snaps 13. The catamenial bandage 14 is fastened at one end to the lower end of the flap 10, and at its other end to the sheet 11, 45 by means of safety pins or other suitable fasteners.

The herein described construction enables the shield and the waist-band to be used independently of each other. Hence, when 50 the shield is to be dispensed with the snaps 8 and 13 are pulled apart, whereupon the shield can be removed without disturbing the adjustment of the waist-band. The detachability of the parts also makes them 55 easier to wash, and to be kept in a sanitary condition.

I claim:

The combination of a waist-band having a depending flap intermediate its ends, a 60 shield to which the ends of the waist-band are detachably connected, an apron detachably connected to that portion of the waist-band having the depending flap and overlapping the latter, and a detachable connection between said shield and the lower end 65 of the flap.

In testimony whereof I affix my signature in presence of two witnesses.

ANTOINETTE VOSS.
